INVENTOR
Theodor Rensing,
BY Chas. W. Gerard.
ATTORNEY.

UNITED STATES PATENT OFFICE.

THEODOR RENSING, OF KANSAS CITY, MISSOURI.

SWIMMING DEVICE.

Application filed November 14, 1927, Serial No. 233,099.

The present invention relates to devices for use in swimming, and aims to provide a novel and improved device of this character which is adapted to be removably clasped to each of the ankles of a swimmer, for enabling him to make use of a greater area or expanse of water in propelling himself by the action of his legs.

Accordingly, I have devised a swimming contrivance adapted to be attached to each ankle, and comprising a series of foldable and expandible pocket elements adapted to open during the rearward or swimming stroke of the ankle, and likewise to collapse or fold in the reverse movement thereof.

In carrying my invention into practice, I make use of a pair of bands or cuffs for the ankles, each band or cuff carrying a series of pocket elements adapted to open and collapse in the swimming movements.

It is also sought to provide a device of this character in which provision is made for adjustably securing pocket elements to the band or cuff, in order to accommodate the same to the requirements of the swimmer.

With these general objects in view, as well as minor objects as will appear in the course of the detailed description, the invention will now be described by reference to the accompanying drawing illustrating one form of construction which I have devised for embodying the proposed improvements, after which those features and combinations deemed to be novel will be set forth and claimed.

In the drawing:—

Figure 1 is a plan view of a device constructed in accordance with the present invention, the same being in opened position;

Figure 2 is a similar view, showing the opposite or inner face of the device;

Figures 3 and 4 are enlarged detail sectional views, representing sections taken on the lines III—III and IV—IV, respectively, of Figure 1;

Figure 5 is a perspective view, on a smaller scale, illustrating the device in position of use, and in folded or collapsed position; and

Figure 6 is a similar view, but illustrating the device in open or expanded position.

Referring now to the drawing in detail, this illustrates the improved device as comprising a band or cuff 10 of suitable flexible material, such as canvas or the like, and provided at its opposite ends with straps 12 and suitable

buckle devices 14 whereby the cuff or band may be removably clasped to one of the ankles of the swimmer, as illustrated in Figures 5 and 6.

To the exterior of the band or cuff 10 is attached a plurality of foldable and expandible pocket elements, comprising a series of panel elements 15, preferably of suitable water-proof material, and connected by a series of foldable or collapsible gusset elements 16, the end panels being provided with snap fastening elements 17 or equivalent devices, for securing the pocket elements together at one of the sides of the ankle, or at that point where the strap fastenings 12 and 14 occur for securing the cuff or band 10 in place. Flexible stay elements 23 connect the lower portions of the panels 15 to the outer face of the cuff 10, and serve to limit the outward or expanding action of the pocket elements. The panels 15 may be of molded material, if desired, so as to conform closely to the shape of the foot and ankle, and I preferably reinforce the panels by means of a resilient stiffening material, such as wire 18 extending about the margin of each panel, as clearly illustrated in Figures 3 and 4. For further strengthening purposes, I also make use of a suitable cord 19 extending continuously along the lower margin of the entire pocket structure, including both the panels 15 and the intervening gusset elements 16, as illustrated in Figure 4.

The upper ends of the panel members 15 are provided with a row of snap socket elements 20 for attaching the pocket structure to either one of a pair of knob elements 21, the latter being provided in two spaced rows along the upper margin of the band or cuff 10, whereby the pocket structure may be secured at slightly different elevations upon the ankle of the swimmer. At the upper ends of the panel members of each device is also provided a band or strap 24 of elastic material extending through loops formed by cutting slits 26 in the upper ends of the panels 15, and adjustably secured in place by a buckle 27. The action of these bands is to assist in the folding or collapsing of the pocket elements, as well as to maintain the devices in snug position about the ankles so long as the swimmer is out of the water.

It will thus be seen that I have devised a simple and yet practical and efficient device for carrying out the desired objects of the

invention. In use, the swimmer simply fastens the cuffs to the ankles at the desired height, by means of the straps 12 and buckles 14, these coming at one of the sides of each 5 ankle. The pocket structure is then adjusted, by means of the snap fastenings 20—21 to the desired elevation to suit the needs of the swimmer, the lower the panels 15 the wider will the pocket elements be allowed to open, 10 as limited by the flexible stays 23. The fastenings 20 and 21 also afford a slight adjustment according to the size of the person making use of the device.

By the use of this improved swimming contrivance, the user is enabled to exert a greater propelling force in the water, due to the increased area or expanse provided by the pocket structure of each device as these are opened in the rearward or swimming stroke 20 of the ankles, the reverse stroke obviously resulting in the folding or collapsing of the pocket structures, in an obvious manner. It will also be understood that the device will be useful in enabling a novice to acquire the 25 art of swimming, since it will afford him ad-

ditional support and propelling force in the leg movements, and materially increase his confidence due to the increased efficiency in the leg movements.

While I have illustrated and described what I now regard as the preferred form of construction for embodying the invention, I desire to reserve the right to make such changes or modifications as may fairly fall within the scope of the appended claim. 30

Having thus described my invention, what I claim and desire to secure by Letters Patent is:

A swimming device comprising a band or cuff adapted to be removably clasped to the ankle, a plurality of foldable and expandible pocket elements carried by said band or cuff and adapted to open in the rearward swimming stroke of the ankle, and an elastic member encircling the upper ends of said elements 40 and acting to maintain the same normally in folded position. 45

In witness whereof I hereunto affix my signature.

THEODOR RENSING.
